[57] CLAIM

An ornamental design for a diagnostic device for measuring biochemical characteristics of microorganisms and the like, substantially as shown and described.

DESCRIPTION

FIG. 1 is a top perspective view of a diagnostic device for measuring biochemical characteristics of microorganisms and the like;

FIG. 2 is a side elevational view of the diagnostic device for measuring biochemical characteristics of microorganisms and the like;

FIG. 3 is a top plan view of the diagnostic device for measuring biochemical characteristics of microorganisms and the like of FIG. 1; and

FIG. 4 is a rear elevational view of the diagnostic device for measuring biochemical characteristics of microorganisms and the like of FIG. 1 with the cover closed.

FIG. 4

FIG. 3

FIG. 2
